SEWING MACHINE

Charles F. Rubel, Chicago, Ill., assignor to Union Special Machine Company, Chicago, Ill., a corporation of Illinois

Application August 21, 1943, Serial No. 499,483

17 Claims. (Cl. 112—248)

1

This invention relates to an improved sewing machine construction, and more particularly to improved devices for supplying, manipulating, controlling and guiding the needle thread of such a machine.

An important object of the invention has been to provide simple and effective means for handling the needle thread and insuring its proper disposition and control under varying circumstances encountered in the normal operation of a sewing machine.

A further object has been to provide a construction which is simple and inexpensive to produce and easy to utilize and which will reduce to a minimum the danger of thread breakage, while at the same time insuring proper stitch formation.

Another object has been to provide thread handling devices of the above character constructed and arranged to prevent the winding and entanglement of thread in the event of thread breakage and which will thus eliminate both wastage of thread and loss of time in removing tangled or wound-up thread and in re-threading the machine.

In attaining the foregoing objects, various improved features have been embodied in the machine. Simple and reliable means have been provided for releasing the tension upon the needle thread whenever the presser foot is raised out of contact with the work, thereby enabling the operator to manipulate the thread freely. The thread-tensioning means has been located at a particularly advantageous point in relation to other thread handling or manipulating devices. Means of simple character have also been provided and advantageously located for regulating the supply of the needle thread in response to variations in thickness of the work being stitched. A very simple arrangement has been provided, moreover, to facilitate threading and effective means have been included, in conjunction with suitable take-up mechanism, for eliminating the danger of thread wastage, in the event of thread breakage, by shifting the end or ends of the thread away from the zone of action of the take-up member.

Other objects, features and advantages of the invention will appear from the detailed description of an illustrative embodiment of the invention which will now be given in conjunction with the accompanying drawings, in which:

Fig. I is a view partly in front elevation and partly in longitudinal section through a sewing machine embodying the invention.

2

Fig. II is an end view of the machine as seen from the left in Fig. I.

Fig. III is an elevational view of the needle head portion of the machine, taken from the same end as Fig. II, but with various cover plates removed.

Fig. IV is a view of the needle head of the machine, largely in front elevation but partly in section and having portions broken away for clearer illustration of certain parts.

Fig. V is a detail view of a thread-guiding and removing element forming part of the take-up mechanism.

Fig. VI is a longitudinal sectional view through a portion of the overhanging arm of the machine including the needle head.

Fig. VII is a detail view in longitudinal section through a thread tensioning device embodied in the machine.

Fig. VIII is an end elevation of the needle head of a modified construction.

Fig. IX is a front elevation of the needle head portion of the overhanging arm of the modified construction, and

Fig. X is a detail view showing a thread-guiding and removing element embodied in the modified construction.

For purposes of illustration, the invention has been shown applied to a machine generally of the type disclosed in the Christensen et al. Patent No. 2,113,572, granted April 12, 1938. This machine has a main frame comprising a base portion 10 provided with a work supporting surface 11 and carrying at one end an upwardly extending standard 12 from the upper end of which an overhanging arm 13 projects over the work support. At its free end the overhanging arm carries a needle head 14. The machine is operated from a combined hand wheel and pulley 15, which receives power by means of a belt from any suitable source and transmits the power to the interior of the machine by means of a shaft 16 on which the pulley is mounted. Shaft 16 extends through the overhanging arm into the needle head and within the latter has secured thereto a crank arm 17 carrying a crank pin 18 connected by a link 19 with a collar 20 adjustably secured to a needle bar 21. This bar carries a needle 22 at its lower end, the eye of the needle being reciprocated between a point well above the work support, as shown in Fig. I, and a point below the work support upon each revolution of the shaft 16.

Within the standard 12 of the frame there is secured to the shaft 16 a gear 23 which meshes

with a gear 24 rotatable upon a stationary shaft 25 in the standard. Gear 24 meshes with a gear 26 secured to a shaft 27 which extends longitudinally of the base of the machine. At an intermediate point a gear 28 is secured to the shaft 27, this gear meshing with a gear 29 secured to a shaft 30 carrying at its outer free end the rotary component 31 of a rotary hook. This hook may be of any suitable construction and, as illustrated, includes a stationary component 32 within, and in bearing engagement with, the rotary component. The gearing 28 and 29 is such as to impart two revolutions to the shaft 30 for each revolution of the shaft 27 which rotates at the same angular speed as the shaft 16.

Any suitable means may be provided for feeding the work in proper relation to the stitch-forming devices comprising the needle 22 and the rotary hook. Such feed means may include a feed dog 33 adjustably mounted by means of a screw 34 on a feed bar 35, the opposite end of which is pivotally supported by a rocker member 36. This member is oscillated by means of a pitman 37 connected with an eccentric (not shown) carried by the shaft 27 to impart the feeding and return movements to the feed dog. Lifting and lowering movements are imparted to the feed dog by means of an arm 38 connected with the feed bar 35 and having attached to its outer, lower end a link 39 connected with an eccentric or crank pin (not shown) at the end of the shaft 27. For further details as to the construction and operation of the work feeding devices and also the stitch forming devices, reference may be had to the above-mentioned Christensen et al. patent or to the patent to Sauer et al., No. 2,035,508, granted March 31, 1936.

Cooperating with the feed dog in advancing the work along the work supporting surface is a presser foot 40 secured to the lower end of a presser bar 41 which is yieldingly urged downwardly by means of a spring 42 (Fig. III) acting between the lower end of an adjustable screw-threaded sleeve 43 and a surface on a block 44 secured to the presser bar. For the purpose of lifting the presser bar to release the work, suitable devices are provided including a link 45 adapted to be operated by a foot treadle or the like (not shown). This link is connected with the end of a lever 46 pivotally mounted on the frame of the machine at the needle head. A spring 47 urges the lever in a clockwise direction (Fig. III). A broad, flat link 48 attached by a screw 49 to the inner end of the lever 46 has its lower end connected at 50 (Fig. VI) with an extension 51 projecting laterally from the upper end of a sleeve 52 slidably mounted on the presser bar. Due to the action of spring 47, the sleeve 52 is normally held in the position indicated in Figs. III and VI with a clearance between the same and the bottom of block 44. When the lever 46 is operated, however, by the link 45, the sleeve 52 will be raised into engagement with the block 44 and will then lift the block and the presser bar against the action of spring 42. Both the presser bar and needle bar 21 are mounted for reciprocation in suitable bearings in the needle head at the outer end of the overhanging arm 13 of the main frame. Rotation of the presser bar and of the sleeve 52 is prevented by cooperation of laterally projecting portions 44a of the block 44 and 52a of the sleeve 52 with a slot in the needle head. (See Fig. III.) A cover member 53, preferably formed of plastic material, is

applied over a portion of the arm 13 and needle head 14 to enclose certain parts and produce a neater appearance. This cover member may be secured by a pair of screws 53a (Fig. III) and a nut 53b. (Fig. I.)

The needle thread 54 (Fig. I), derived from any suitable source, is passed through openings in a guide pin 55 carried by the nut 53b at the top of the main frame and then through openings in a guide 56 mounted on the side of the overhanging arm at or adjacent the needle head. From the guide 56 the thread is passed around a thread tensioning device indicated generally at 57, which will be hereinafter described in further detail. From the thread tensioning device the thread is led under a hooked portion 58 of a thread guide having a long rod-like extension 59 inserted in an opening provided in an upwardly extending portion 60 of the block 44. This arrangement is such that as the presser foot is raised and lowered, in response to variations in the thickness of the work, the guide 58 will be correspondingly raised and lowered and will either yield or take up extra thread as required for proper stitch formation. From the guide 58 the thread is led across the outer edge of a double-lobed cam member 61 (Fig. II) forming part of the thread take-up. The thread is then passed through an eyelet 62 into the interior of the take-up mechanism and thence over a slotted element 63 which projects laterally from the cam 61 and is carried through an orbital path upon rotation of the latter. From the take-up element 63 the thread is led downwardly to and through a fixed guide 64 and thence to the eye of the needle, from which it extends to the work.

For the purpose of rotating the cam member 61 and carrying the element 63 through a circular, orbital path, the cam member is secured by means of screws 65 to a disc-like flange carried by the outer end of a shaft 66 journaled in suitable bearings provided in the needle head 14. At its inner end shaft 66 carries a gear 67 which meshes with a gear 68 secured to the shaft 16. Through these connections the shaft 66, and hence the cam member 61, will be given one revolution for each revolution of the shaft 16.

The principle of operation of the take-up devices, including the cam 61 and the slotted take-up element 63, is the same as for the corresponding parts of the take-up described in detail in my Patent No. 2,400,602, entitled "Sewing machine" and granted May 21, 1946, and as more fully set-forth in the Rubel et al. Patent No. 2,398,667, entitled "Sewing machine" and granted April 16, 1946. For further details as to the take-up action of the device, reference may be had to the above-identified patents.

In the path of the needle thread between the eyelet 62 and the fixed guide 64 there is provided a stationary member 69 constituting a combined positioning and removing member. Referring particularly to Fig. V, the member 69 is provided with a relatively deep recess 70, the center line of which is substantially in line with the eyelet 62. In the normal operation of the take-up, the two sections of the slotted element 63 will, upon each cycle, pass at opposite sides of the member 69, which is curved to conform with the slot in the element 63, both being curved about the axis of the shaft 66. As the element 63 approaches and passes through the lower portion of its cycle, the thread will be guided into the recess 70 by the surfaces 71 and 72 (Fig. V) of the member 69 and it will be picked up from the

bottom of the recess by the forward or leading edges of the element 63 as the two sections of the latter pass along the opposite sides of the member 69 and are carried above this member. Should the needle thread become broken in the course of a stitch-forming operation, and should it, as a result of tension at the time of breakage or for any other reason, become so engaged with the element 63 as to be in danger of becoming entangled therewith, provision is made for removing the thread from such element during the same cycle in which it has become so engaged and shifting it to a point beyond the end of the element. This prevents the wastage of thread, which frequently occurs in rotary take-up mechanisms that permit continuous winding of the thread about a portion of the take-up. Moreover, there is not only a saving of thread but also a saving of time since the operator does not lose valuable time in the removal of wrapped thread. The automatic removal of the improperly engaged thread is effected by the inclined lower edge 73 of the member 69 (Fig. V). It will be apparent that if the thread has become improperly positioned across the leading edges of the two parts of the element 63, as the latter approaches the member 69, the thread so extending across the slot in the element 63 will engage the edge 73 and will be cammed by the latter toward the left (Figs. IV and V) to a point beyond the end of the element 63. This removal of the thread will take place as often as the thread becomes improperly engaged with the element 63 and in the same cycle in which it becomes so engaged.

A feature of the invention, in connection with the foregoing, is that breakage of the thread in the course of operation of the machine will almost invariably occur at the point in contact with the edge of the cam 61 at the time of maximum take-up action, i. e. as the stitch is being set. This is because the usual causes of breakage common to take-up mechanisms of the prior art have been eliminated by the use of the cam which eliminates any excessive slack in the thread at all times. As a result of this, there is only a short loose-end of the thread which is in danger of becoming entangled with the element 63 and this loose end is connected with the work rather than the source of thread supply. Accordingly, the danger of wrapping of the thread about the element 63 is reduced to a minimum and, in any event, any thread which becomes improperly engaged with element 63 will be quickly removed in the manner explained above.

For supporting the member 69 between the paths described by the two sections of the element 63, at opposite sides of the slot, the member is provided with a radially extending arm 74 secured by a screw 75 and dowel pins 76 to a plate 77. This plate in addition to its function as a support for the member 69, serves also as a partial closure and guard for the take-up devices. It is secured to the frame of the machine by means of an over-turned flange portion 78 which is welded or otherwise secured to a bracket 79. The latter, which is slotted to permit the cam member 61 to extend therethrough has a lower, horizontal extension 80 secured by a screw 81 to a plug 82 mounted in a boss 83 extending inwardly into the needle head frame and forming an integral part thereof. A similar boss in prior constructions has received and retained thread tensioning means. Screw 84 is provided to retain the plug in the boss. At its upper end

the bracket 79 is provided with a lateral extension 85 secured by a screw 86 to a bar 86a projecting forwardly (Fig. III) from the needle head. The upper portion of the bracket is bent outwardly, as shown, to serve as a stripper for the thread as it is carried by the cam member 64. Spaced inwardly a slight distance from the closure 77 is a second partial closure 87 which covers and guards another part of the path of the take-up devices. The member 87 is secured by screws 88 to lugs 89 projecting inwardly from a flange 90 connected with a plate 91 secured to the end of the needle head.

The relationship between the various elements of the take-up and the enclosure for the same is such that threading of the take-up may be very readily accomplished even though the take-up is largely concealed. After passing the thread through the eyelet 62, the operator simply needs to carry the thread upwardly over the edge of the closure 77 and partly around the shaft 66 and element 63. Regardless of the position of the element 63, the thread may be properly positioned about this by a simple sweep of the hand around the periphery of the closure 77, with the fingers of the operator, which grasp the thread, extending inwardly over the edge of the closure 77. This sweeping movement of the hand of the operator should be continued until the thread is carried beyond the end 82 of the plate 87 and then by a slight inward movement the thread may be carried behind this projecting end of the plate 87 before the downwardly extending portion of the thread is passed through the fixed guide 64.

35 Referring now to Figs. III and VII, the details of the thread tensioning means will be described. This means comprises a main supporting hub 93 which passes through an opening in the cover member 53 and has screw-threaded engagement 40 with a bracket 94 which is secured to the needle head frame by a screw 94a (Fig. VI). A sleeve 95 is mounted within the hub 93 and is retained in fixed relation thereto by a set-screw 96. Sleeve 45 95 extends into needle head 14, one end terminating therein as shown in Figure III. Around the sleeve 95, near its outer end, is carried a pair of thread clamping discs 97 and 98 which are urged together by a spring 99 acting at its outer end against an adjustable thumb nut 100 50 threaded upon the end of the sleeve 95 and bearing at its inner end against a washer 101 which is forced by the spring against the disc 98. The latter in turn is forced against a shoulder at the 55 outer end of the hub 93. Washer 101 has a diametrically extending cross-piece 102 which cooperates with a slot in the end of the sleeve 95. Within the sleeve there is slidably mounted a pin 103 which at its outer end 104 engages the 60 cross-piece 102 of the washer and at its inner end extends slightly beyond the end of the sleeve 95, as shown in Fig. III. The inner end of the pin is normally opposite a bent-over, camming extension 105 of the link 43 which serves to lift 65 the presser bar. After the presser bar has been raised by this link to a predetermined extent, i. e., beyond the extent to which it would be raised by mere variation in thickness of the work, the cam portion 105 will engage the rod 103 and force it to the right (Fig. III). The opposite 70 end 104 of the rod will then engage the cross-piece 102 of the washer and shift it to the right to remove the pressure of the spring 99 from the clamping discs 97 and 98. This will permit 75 the free movement of the thread through the

tensioning means. A check wire 106 is also included in the tensioning device, this being constructed and arranged to operate in the manner set forth in the Christensen et al. Patent No. 2,394,365, entitled "Thread control mechanism for sewing machines" and granted February 5, 1946.

Referring now to Figs VIII, IX and X, a modified construction is shown. This form of the invention is simplified slightly by the omission of the plate 77 of the form described above. The parts of the modified construction which correspond with those of the first construction are designated by similar reference numerals with the subscript "a." Thus, a thread tensioning device 57a is provided from which the thread is led to a guide 58a adapted to be raised and lowered with the presser foot in accordance with variations in the thickness of the work, thereby automatically varying the amount of thread supplied in accordance with the requirements. From the guide 58a the thread is led across the edge of the two-lobed cam 61a and is then passed through an eyelet 62a, thence over a slotted take-up element 63a carried by the cam member, and then downwardly to the fixed guide 64a and on to the needle and the work, as before. Cam member 61a is secured by screws 65a to a flange at the end of a shaft 66a driven from the main shaft of the machine in the same manner as shaft 66.

A combined thread guiding and removing member 69a is provided in the form shown in Fig. X. This differs from member 69 primarily in the form of the portion by which it is attached to the supporting means. It has surfaces 71a, 72a and 73a which function in the same manner as the corresponding surfaces of member 69. Member 69a, however, is secured directly by means of a screw 75a and dowel pins (not shown) that extend through openings 76a to a front bracket and closure plate 79a, similar to bracket 79. Cam member 61a extends, at times, through a slot in the bracket 79a. The latter is secured to the frame of the machine by means of screws 81a and 86a passing through extensions 80a and 85a, respectively, the screw 81a cooperating with a plug 82a projecting from the frame of the machine.

As indicated above, the take-up mechanism of this embodiment is not enclosed as fully as in the first form. Plate 77 is omitted from the end of the machine and a plate 87a, which corresponds in shape and function with plate 87, has been shifted to the extreme outer end of the take-up housing extending from the needle head. It is held by screws 88a engaging in lugs 89a extending inwardly from a flange 90a forming part of the take-up housing, this being integral with or otherwise secured to a closure plate 91a for the needle head. In threading this take-up mechanism, it is simply necessary to pass the thread around the element 63a, after inserting it through the eyelet 62a, and then around the end 92a of the plate 87a to a position in back of this end. In all other respects the modified construction may suitably be identical with the first embodiment described above.

While a preferred form of the invention has been described in considerable detail and certain modifications have been suggested, it will be understood that numerous other changes may be made without departing from the general principles and scope of the invention.

What I claim is:

1. In a sewing machine a reciprocatory needle

bar having a thread carrying needle, a rotary take-up for the needle thread which comprises a slotted thread engaging element having a free end and mounted for orbital movement, and a member adapted to engage and position a portion of the needle thread during each complete revolution of said rotary take-up and arranged to pass through the slot in said element in the course of its orbital movement, said member being constructed and arranged to force outwardly beyond the free end of said element any thread which may become improperly engaged with the same due to breakage.

2. In a sewing machine a reciprocatory needle bar having a thread carrying needle, a rotary take-up for the needle thread which comprises a rotary member, a slotted thread engaging element having a free end, extending laterally from said member and carried through a circular path upon rotation thereof, and a thread positioning member arranged to pass through the slot in said element in the course of its orbital movement, said second mentioned member being constructed and arranged to force outwardly beyond the free end of said element any thread which may become improperly engaged with the same due to breakage.

3. In a sewing machine a reciprocatory needle bar having a thread carrying needle, a rotary take-up for the needle thread which comprises a rotary member, a slotted thread engaging element having a free end, extending laterally from said member and carried through a circular path upon rotation thereof, and a stationary thread positioning member disposed in spaced relation to the rotary member arranged to pass through the slot in said element in the course of its orbital movement, said second mentioned member having its edge which first enters said slot so inclined as to force outwardly beyond the free end of said element any thread which may become improperly engaged with the same due to breakage.

4. In a sewing machine a reciprocatory needle bar having a thread carrying needle, a rotary take-up for the needle thread which comprises a rotary member, a thread engaging element having a free outer end, projecting laterally from said member and carried through an orbital path upon rotation thereof, said element having a slot extending inwardly from its outer end, and a fixed thread positioning member in the path of said element arranged to traverse the slot therein during each revolution of the first member, said fixed member having its edge which first enters said slot so formed as to cam outwardly beyond the outer end of said element any thread which may become improperly engaged with the same due to breakage.

5. In a sewing machine a reciprocatory needle bar having a thread carrying needle, a rotary take-up for the needle thread which comprises a rotary member, thread engaging means having a free outer end, projecting laterally from said member and carried through an orbital path upon rotation thereof, said means having radially spaced portions providing a passage therebetween from the outer end of said means, and a fixed thread positioning member in the path of said means arranged to traverse said passage during each revolution of the first member, said fixed member having its edge which first enters said passage so formed as to cam outwardly beyond the outer end of said means any thread

which may become improperly engaged with the same due to breakage.

6. In a sewing machine a reciprocatory needle bar having a thread carrying needle, a rotary take-up for the needle thread which comprises a rotary member having a peripheral surface adapted to impart a take-up action to the thread, thread engaging means having a free outer end, projecting laterally from said member and carried through an orbital path upon rotation thereof, said means having radially spaced portions providing a passage therebetween from the outer end of said means, said means constituting the only portion of said take-up with which thread is likely to become entangled upon breakage, and a fixed thread positioning member in the path of said means arranged to traverse said passage during each revolution of the first member, said fixed member having its edge which first enters said passage so formed as to cam outwardly beyond the outer end of said means any thread which has become improperly engaged with the same due to breakage.

7. In a sewing machine a reciprocatory needle bar having a thread carrying needle, a rotary take-up for the needle thread which comprises a rotary member, thread engaging means having a free outer end, projecting laterally from said member and carried through an orbital path upon rotation thereof, said means having radially spaced portions providing a passage therebetween from the outer end of said means, a fixed thread positioning member in the path of said means arranged to traverse said passage during each revolution of the first member, said fixed member having its edge which first enters said passage so formed as to cam outwardly beyond the outer end of said means any thread which may become improperly engaged with the same due to breakage, a partial closure spaced slightly from said rotary member and parallel therewith, said closure enabling the free passage of the thread around said thread engaging means in the threading of the machine regardless of the position of said means in its cycle.

8. In a sewing machine a reciprocatory needle bar having a thread carrying needle, a rotary take-up for the needle thread which comprises a rotary member, thread engaging means having a free outer end, projecting laterally from said member and carried through an orbital path upon rotation thereof, said means having radially spaced portions providing a passage therebetween from the outer end of said means, a fixed thread positioning member in the path of said means arranged to traverse said passage during each revolution of the first member, said fixed member having its edge which first enters said passage so formed as to cam outwardly beyond the outer end of said means any thread which may become improperly engaged with the same due to breakage, and a plurality of spaced partial closure members in front of said rotary member and parallel therewith, said closure members enabling the free passage of the thread around said thread engaging means in the threading of the machine regardless of the position of said means in its cycle.

9. In a sewing machine a reciprocatory needle bar having a thread carrying needle, a rotary take-up for the needle thread including a bifurcated thread-engaging member mounted for movement in an orbital path, means for imparting reciprocation to said needle bar and orbital movement to said thread-engaging mem-

70
75

ber in timed relationship, and stationary means for positioning the thread in the path of said member, said last mentioned means being disposed intermediate the paths described by the bifurcated portions of said thread-engaging member and constructed and arranged to cooperate with said thread-engaging member in the event of thread breakage in such manner as to cause the end of a broken thread to be shifted out of the path of said thread-engaging member.

10. In a sewing machine a reciprocatory needle bar having a thread carrying needle, a rotary take-up for the needle thread including a laterally projecting bifurcated thread-engaging member mounted for movement in a circular path, means for imparting reciprocation to said needle bar and rotary movement to said thread-engaging member in timed relationship, and stationary means for positioning the thread in the path of said member, said last mentioned means being disposed intermediate the paths described by the bifurcated portions of said thread-engaging member and constructed and arranged to cooperate with said thread-engaging member in the event of thread breakage in such manner as to cause the end of a broken thread to be shifted out of the path of said thread-engaging member.

11. In a sewing machine, a reciprocatory needle bar having a thread carrying needle, a rotary take-up for the needle thread including a bifurcated thread-engaging member mounted for movement in an orbital path and having leading thread-engaging edges, means for imparting reciprocation to said needle bar and orbital movement to said thread-engaging member in timed relation, and stationary means for positioning the thread in the path of said member, said stationary means being disposed adjacent the path described by said thread-engaging member and arranged to pass between the thread-engaging edges of said member, said stationary means being constructed and arranged to cooperate with said thread-engaging member in the event of thread breakage in such manner as to cause the end of a broken thread to be shifted out of the path of said thread-engaging member.

12. In a sewing machine, a reciprocatory needle bar having a thread carrying needle, a rotary take-up device for said needle thread, a rotatable shaft supporting and actuating said take-up device and means for reciprocating said needle bar and rotating said shaft in timed relation, said take-up device including a thread-manipulating element having a free end spaced from and extending beyond the end of said shaft and having a plurality of radially spaced leading thread-engaging edges, means determining the point of normal initial engagement of said edges with said thread, and stationary means spaced from and arranged to pass between the thread-engaging edges of said element and constructed and arranged to cooperate with said element during each revolution of said take-up device to remove thread abnormally engaged by said edges in advance of said point of normal initial engagement and shift the same to a point out of the path of said thread-engaging edges of said element and beyond the free end of said element.

13. In a sewing machine a reciprocatory needle bar having a thread carrying needle, a rotary take-up device for said needle thread, a rotatable shaft supporting and actuating said take-up device and means for reciprocating said

needle bar and rotating said shaft in timed relation, said take-up device including a single thread-manipulating element spaced from and extending beyond the end of said shaft and having a plurality of radially spaced, leading, thread-engaging edges, means determining the point of normal initial engagement of said edges with said thread, and means disposed between the paths described by said leading edges in the course of their rotation constructed and arranged to cooperate with said element to remove thread abnormally engaged by said edges in advance of said point of normal initial engagement and shift the same to a point out of the path of said element.

14. In a sewing machine a reciprocating needle bar having a thread-carrying needle, a rotary take-up device for said needle thread, a rotatable shaft supporting and actuating said take-up device and means for reciprocating said needle bar and rotating said shaft in timed relation, said take-up device including a thread-manipulating element spaced from and extending beyond the end of said shaft and having a plurality of radially spaced, leading, thread-engaging edges, means determining the point of normal initial engagement of said edges with said thread, and means constructed and arranged to be received in the space between said thread-engaging edges and to cooperate with said element during each revolution of the take-up device to remove thread abnormally engaged by said edges in advance of said point of normal initial engagement and shift the same to a point out of the path of said element, said last-named means comprising a stationary element provided with an inclined thread-engaging face.

15. In a sewing machine having a work support, a needle bar having a thread carrying needle, a rotary hook cooperating with said needle in stitch formation, means for operating said needle bar and said hook, a rotary take-up for the needle thread comprising a cam member driven by said operating means, a presser bar carrying a presser foot, means for yieldingly urging said presser bar downwardly to engage said presser foot with the work, means for lifting said presser bar to disengage said presser foot from the work, a first thread guiding means disposed opposite one face of said cam member, a second thread guiding means disposed opposite the other face of said cam member, one of said guiding means being adjacent said cam member and normally engaging said needle thread in a substantially horizontal plane through the axis of said rotary take-up, and means connecting said

last mentioned guiding means with said presser foot for movement in unison.

16. In a sewing machine having a work support, a needle bar having a thread carrying needle, a rotary hook cooperating with said needle in stitch formation, means for operating said needle bar and said hook, a rotary take-up for the needle thread driven by said operating means, a presser bar carrying a presser foot, means for yieldingly urging said presser bar downwardly to engage said presser foot with the work, means for lifting said presser bar to disengage the foot from the work, thread tensioning means arranged to engage said needle thread at a point substantially in line horizontally with the axis of said take-up, a guide for said thread intermediate said tensioning means and said take-up, and means connected with said presser bar for shifting said guide and for releasing said tensioning means upon predetermined upward movement of said presser bar.
17. In a sewing machine, stitch forming means adapted to carry a thread, means for guiding thread along a path from a source of supply to said stitch forming means, a rotary take-up for said thread in said path, said take-up comprising an element having a free end and mounted for movement through a circular path, said element having a slot in the free end, and a fixed thread positioning member in the path of said element arranged to traverse said slot as said element is moved along its circular path, said member having a camming edge adapted to shift thread which becomes improperly engaged with said element to a point beyond the free end of said element.

CHARLES F. RUBEL.
